US00D945270S

(12) **United States Design Patent** (10) Patent No.: **US D945,270 S**
(45) Date of Patent: **** Mar. 8, 2022**

(54) **PACKAGING BOTTLE**

(71) Applicant: **Blueship Okinawa Co., Ltd.**, Okinawa (JP)

(72) Inventor: **Hiroumi Keimatsu**, Naha (JP)

(73) Assignee: **BLUESHIP OKINAWA CO., LTD.**, Okinawa (JP)

(**) Term: **15 Years**

(21) Appl. No.: **35/509,704**

(22) Filed: **Dec. 26, 2019**

(80) **Hague Agreement Data**

Int. Filing Date: **Dec. 26, 2019**

Int. Reg. No.: **DM/205875**

Int. Reg. Date: **Dec. 26, 2019**

Int. Reg. Pub. Date: **Jun. 26, 2020**

(30) **Foreign Application Priority Data**

Jul. 1, 2019 (JP) 2019-014775

(51) LOC (13) Cl. **09-01**

(52) U.S. Cl.

USPC **D9/546**; D9/563
